UNITED STATES PATENT OFFICE.

CHARLES C. HUFFMAN, OF CHICAGO, ILLINOIS, ASSIGNOR TO SUNBEAM CHEMICAL COMPANY, OF CHICAGO, ILLINOIS, A CORPORATION OF ILLINOIS.

UNIVERSAL RED DYE AND METHOD OF PRODUCING THE SAME.

1,274,049.

Specification of Letters Patent. Patented July 30, 1918.

No Drawing.

Application filed September 24, 1917. Serial No. 192,874.

To all whom it may concern:

Be it known that I, CHARLES C. HUFFMAN, a citizen of the United States, and resident of Chicago, in the county of Cook and State of Illinois, have discovered a certain new and useful Universal Red Dye and Methods of Producing the Same, of which the following is a specification.

My discovery relates to dyes and particularly to a novel red dye soap having peculiar and advantageous qualities.

I am aware that heretofore dyes have been incorporated in soaps with the object in view of providing a simple carrier for the dye and fairly satisfactory results may be secured if certain neutral dyes are employed and if the water in which the substance is used is of exactly the right temperature.

One of the most important features of my novel discovery is that the shade of color which is secured in the use of the article is the same whether a large or small quantity is employed and whether it is used in hot or cold water. It is preferably used with hot water for the reason that the soap will not act to thoroughly cleanse the article unless the water is hot. The effect of deepening the shades by the use of hot water is not present and this is of great importance if it be desired to reproduce certain colors.

The ordinary user has no means of determining whether the same temperature is employed in each instance. Neither would he be able to determine whether exactly the same quantity of the dyeing material was employed. By the use of my product the colors may be duplicated with ease and certainty.

My improved dye soap should not be confused with those in which the soap acts merely as a carrier or vehicle for the dye, as the following description will show that the final product is the result of peculiar reactions which take place between the dye and the elements of the soap and which product could not be secured by the use of the materials heretofore employed or as heretofore combined. By reason of the novel process of compounding and the selection of substances which enter into the compound, a dye is produced which is equal if not superior to those which require boiling and the addition of a mordant for setting the color.

An important distinction of my dye soap

over any such article heretofore produced is that the soap is manufactured by the cold process and many advantages result therefrom.

A further important distinction of the dyes produced by me is that they are alkali proof, irrespective of the characteristics of the dyes, that is, basic neutral or acid, before combining in the soap.

A still further distinction is that the dyes are universal, that is, adaptable to either cotton, wool, silk or flax, or mixtures thereof.

One of the important advantages following the use of the method disclosed is that of allowing the glycerol, which is a by-product of the saponification process, to remain in the product. This is liberated when the soap is dissolved and co-operates with the dye in attacking the fabric. Furthermore, it assists in fixing the colors following the application of heat, as in the act of ironing, after the fabric has been dried.

The composition and the method of preparing it will now be described in detail.

In order to establish a basis for the proportions of ingredients, it will be assumed that it is desired to produce five gross of one ounce bars of the soap. To produce this quantity, three gallons and forty-two ounces of vegetable oil and one gallon and twenty-four ounces of sodium hydroxid (NaOH) of a specific gravity of 1.40 at 65° F. are combined. The oil or oils used may be varied. Olive, soy bean, raisin, peanut, crude corn, or any vegetable oil may be used separately or combined with cocoanut oil. The proportions of the cocoanut oil and other oils will vary according to weather conditions. Under normal conditions one gallon, fourteen ounces of cocoanut oil will be employed to two gallons, twenty-eight ounces of the other oils. In warm, dry weather the proportion of cocoanut oil should be lessened and increased in cool, damp weather.

The oil and caustic soda are mixed until saponification is nearly complete at which time the dye solution is added.

To produce a medium red I employ substantially eight ounces of anilin acid red, which is dissolved in one gallon of boiling water and added to the incompletely saponified soap mixture. The heat of the reaction together with the heat supplied in the boiling water serves to raise the temperature of

the mixture to approximately 122° F., at which time the color acid reacts with the excess of sodium hydroxid forming the sodium salt of the color acid with the elimination of a molecule of water. The exact formula of the resulting dye has not been determined. It is, however, materially different from the formula of the anilin acid red and is universal and alkali proof. The 10 different shades, such as flesh, pink, rose pink, etc., are produced by lessening the quantity of the dye employed in the original compound. When the soap is used the color is not changed or deepened by employing 15 a water solution of varying temperatures. The color will be the same whether cold or hot water is used.

To produce orange, salmon and similar shades, red and chrysoidin are separately dissolved, each in two quarts of boiling water and separately added to the soap compound. The chrysoidin solution is first added and after the reaction is complete the red solution is added.

25 Lavender, old rose, purple and similar shades are made by dissolving red and methylene blue, each in two quarts of boiling water. In this instance the red is first added to the soap compound and then the blue. By following the method described there will be no precipitation of the different colors although in ordinary practice this would occur.

After allowing a few minutes for the 35 action to take place and after the dye has become thoroughly mixed with the soap, the soap is poured into molds where it is allowed to remain at a temperature of about 80° F. for forty-eight hours.

40 By comparison of the proportions of vegetable oil and sodium hydroxid it will be noticed that there is a substantial excess of the latter even when the water containing the dye is added. Of course, the amount of 45 the saponifying agent may be varied somewhat but in any case an excess should be employed.

It will be noted that the glycerol is not removed from the product and therefore 50 will be released as the soap is dissolved. It will be absorbed by the fabric along with the dye and will assist in fixing the dye when heat is applied to the fabric as in ironing. It has furthermore, an advantageous 55 effect on the fabric in softening the same and brightening the colors.

In use the soap and the garment or fabric to be dyed are introduced into hot water and the soap is applied directly to the fabric to 60 thoroughly cleanse the same. Even though the soap is applied locally or only in spots the coloring will be even. Furthermore, the hands or container will not be colored.

After the article is cleansed and dyed it is rinsed in cold water and dried in the usual manner. The dye will be found to be alkali proof.

It will be noted that the soap is manufactured by the cold process. By reason of this process of manufacture I am enabled to 70 secure an absolutely uniform product with regard to the colors produced. The low temperatures employed are much more easily controlled and the necessary reaction between the soap and the dye is completed 75 with a certainty which is not possible in a settled soap.

I claim:

1. A universal, alkali proof red dye combined with soap which consists of the reaction products of an anilin acid red which has been added to a soap solution containing an excess of sodium hydroxid, substantially as described.

2. The method of producing a universal, 85 alkali proof anilin acid red dye combined with soap which consists in combining a vegetable oil and a quantity of sodium hydroxid in excess of that required for saponification, then dissolving anilin acid red in 90 hot water and adding the dye solution to the saponified solution just before saponification is completed, then thoroughly mixing, and then molding the soap, substantially as 95 described.

3. The method of producing an alkali proof, universal anilin acid red dye combined with soap, which consists in saponifying a vegetable oil with a substantial excess of the saponifying agent, then dissolving 100 anilin acid red in water and adding the same to the soap solution prior to the complete saponification and without removal of glycerol from the soap, the temperature of the compound after the addition of the dye 105 being raised to substantially 122° F., then allowing the reaction to be completed and finally allowing solidification, substantially as described.

4. A dye soap formed by combining approximately four hundred and twenty-six parts of a vegetable oil and one hundred and fifty-two parts of sodium hydroxid of a specific gravity of 1.40 at 65° F., then adding to the compound just prior to complete saponification, one hundred and twenty-eight parts of hot water in which substantially eight ounces of anilin acid red has been dissolved, substantially as described.

Signed at Chicago, Ill., this 22nd day of September, 1917.

CHARLES C. HUFFMAN.

Witness:

T. D. BUTLER.
